ELECTRODE STRUCTURE AND DEVICE
CONTAINING THE SAMEZed J. Atlee, Elmhurst, and William White Lange,
Chicago, Ill., assignors to General Electric
X-Ray Corporation, Chicago, Ill., a corporation
of New York

Application March 11, 1946, Serial No. 653,504

9 Claims. (Cl. 250—27.5)

1

The present invention relates in general to electronics, and has more particular reference to electron flow devices, including electronic rectifiers, X-ray tubes, thermionic tubes, and other electron flow devices.

An important object of the invention is to provide a new and improved electron flow device embodying electrode structures affording advantageous voltage distribution within the device, and more particularly between the anode and cathode electrodes thereof; a further object being to provide electrode means, in an electron flow device, affording substantially uniform voltage gradient between the anode and cooperating cathode electrodes.

Another important object is to provide cooperating anode and cathode electrodes, wherein the anode comprises a sleeve-like anode shell embracing the cathode; a further object being to form the cathode as an elongated filament, adapted for electron emission and located substantially along the central axis of the anode shell.

Another important object is to provide protective means for guarding the filament against so-called inverse failure, such failure being caused by electrical discharge from anode to cathode as the result of localized anode heating, field emission of electrons from the anode, or gas burst, any of which may cause a sudden reduction in space charge, between anode and cathode, allowing for the release of stored energy from the capacitance of the anode-cathode circuit. Such released energy, if focused upon the filament, may rupture it and render the device inoperable, even though otherwise in good operating condition. A further important object, therefore, is to provide means, in association with the cathode, to receive and withstand sudden discharges of stored energy, whereby to protect the electron emission element of the cathode against rupture or other damage.

Another important object is to provide protective means, of the character mentioned, comprising a projecting arrestor, on the cathode structure, and extending outwardly of the electron emission element and toward the anode, whereby any sudden energy release, for any of the causes heretofore mentioned, may be received and absorbed by said arrestor without damage to the electron emission element.

The foregoing and numerous other important objects, advantages, and inherent functions of the invention will become apparent as the same is more fully understood from the following de-

scription, which, taken in connection with the accompanying drawings, discloses preferred embodiments of the invention.

Referring to the drawings:

5 Fig. 1 is a sectional view taken substantially through an electronic rectifier embodying the present invention;

Fig. 2 is a sectional view taken substantially along the line 2—2 in Fig. 1;

10 Fig. 3 is a view in longitudinal section through a modified form of anode and cathode embodying the present invention; and

Fig. 4 is a sectional view taken substantially along the line 4—4 in Fig. 3.

15 To illustrate the invention, the drawings show an electronic device in the form of a rectifier 11, although the several features of the invention are not necessarily restricted to rectifiers, but may be utilized to advantage, generally, in electronic devices embodying an electron emitting source or cathode and a cooperating anode for receiving emitted electrons. The electron flow device may comprise a sealed envelope 12 of suitable material, such as glass or metal, glass being specifically shown in the drawings. The envelope 12 contains an anode 13 and a cooperating cathode 14. The envelope 12 may be arranged in any suitable, convenient or preferred form. As shown in the drawings, it comprises a tubular glass shell having re-entrant necks 15, 15', at its opposite ends. The anode 13 and cathode 14, respectively, are supported on the said necks at the opposite ends of the envelope. The necks 15, 15' define openings, which are closed by generally cup-shaped seal members 16, 16', made of sheet metal, and each having an annular rim 17, 17' making a glass-to-metal seal 18, 18' with the inwardly extending end of the neck 15 or 15' on which it is mounted.

40 The seal member 16, at one end of the envelope, carries the anode 13, which may comprise a cylindrical shell 19 of suitable anode material, preferably a metal of high conductivity and low electronic emissivity, such as molybdenum. The anode may be supported on the end seal as by means of a suitable bracket 20. This bracket may be of any preferred form, but, as shown, preferably comprises molybdenum, formed to provide a plurality of spaced arms or fingers 21, in position to engage the outer surfaces of the shell 19. The arms 21 may be interconnected, as on a mounting ring 22, which may be secured on the end seal member 16 in any suitable or convenient fashion, to support the shell 19 preferably in concentric alignment within the envelope 12.

To this end, the seal member 16 may be formed with an opening for receiving a stem 23, having a portion extending outwardly of the end of the envelope and a portion extending inwardly of the envelope through the opening in the seal, said stem being sealed in said opening, and the ring 22 being secured upon the inwardly extending end of the stem in any suitable or preferred fashion, as by means of a holding member 24.

The shell 19 is preferably provided with a pair of spaced apart, outwardly pressed, circumferential ribs 25, which engage the arms 21 of the mounting bracket, the shell being secured to said arms in any suitable fashion, and preferably by means of rivets extending through the arms and through the shell at the ribs 25. A collar 26 may be, and preferably is, applied at each end of the shell 19, said collars comprising cylindrical rings of tantalum, columbium, zirconium, or other metal, the same preferably comprising metal having the ability to absorb gas when heated, and thus to perform a gettering function within the envelope of the device. These rings may be welded or riveted or otherwise attached to the ends of the shell, and preferably have portions extending beyond, and snugly curled about, the opposed end edges of the shell 19 to provide well-rounded beads at the opposite ends of the anode shell. The provision of such well-rounded beads serves to improve voltage field characteristics at the opposite ends of the anode shell; and by making said end pieces of gettering material, such as tantalum, columbium, or zirconium, the same may serve, continuously during the service life of the device, to absorb any gaseous impurities which may be released within the envelope, including occluded gases that may be contained in the anode, the cathode, and the material of the envelope itself, and gradually evolved therefrom and released within the envelope during the operation of the device.

The anode thus is mounted on the end seal 16 at one end of the envelope, the cathode 14 being preferably supported on the end seal at the opposite end of the envelope. The cathode, as shown, may comprise an electron emission element 27 in position within and surrounded by the anode shell 19, which is preferably cylindrical. The electron emission element may comprise an elongated filament supported in position concentrically within and preferably axially of the sleeve 19. The emission filament 27 preferably comprises tungsten wire, the same being supported in place on a suitable mounting structure carried by the end seal. This mounting structure may include a disk-like head 28 of metal mounted on the end seal member 16', as by means of a stud 29 which extends through, and is sealed in, an opening formed in the seal member. The stud 29 may have portions extending outwardly of the envelope and another portion extending inwardly thereof, the member 28 being secured on the said inwardly extending portions of the stud. The head may carry a tubular skirt 30, secured, at one end, to the periphery of the disk-like head 28 and extending thence in position enclosing the glass-to-metal seal 18'. The skirt thus encloses a space between the seal member 16' and the head 28, which space is in open communication with the interior of the envelope through the annular space defined by the end of the skirt 30 and the glass-to-metal seal 18' which it encloses. Within the space, thus enclosed, means may be provided for performing an

initial gettering operation, during the manufacture of the device, and, if desired, periodically during the life of the device, in order to insure the maintenance of a high degree of vacuum

5 within the envelope 12, as taught in United States Letters Patent No. 2,260,927, issued to Zed J. Atlee on October 28, 1941.

The opposite ends of the filament 27 are mounted on, electrically connected with, and supported by conductor stems 31 and 32, which are supported on, and electrically insulated from, the head 28, through which they extend, by means of grommets 33 sealed in openings in the head, the stems 31 and 32 extending through the grommets and being supported therein, and insulated therefrom, as by means of glass beads 34 sealed in the grommets around the stems. The end of the stems 31 and 32 may be electrically connected with conductor means 35, 36 extending outwardly of the envelope through sealed grommet means 37 formed in the seal member 16'.

If desired, one of the stems, such as the stem 31, may be rigidly attached to and grounded on the head 28, and need not extend outwardly of the envelope, electrical connection of the stem 31 with external circuits, in such case, being accomplished through the stem 29. It is desirable, however, to provide an insulated conductor, such as the conductor 36, for connecting the stem 32 in an external circuit.

The filament 27 is thus electrically connected outwardly of the envelope, and may be energized for electron emission from an external source of energizing power. One of the support conductors 35 is preferably formed to provide spaced apart loops 38 at intervals in position encircling the emission filament 27, in order to shield the filament against mechanical displacement thereof under the influence of electrostatic stress fields that may be set up between the filament and the surrounding anode shell 19, as a result of the high operating potential applied therebetween when the device is in operation. Such electrostatic fields may exert a mechanical effect upon the relatively weak filament 27 and pull it out of position laterally, unless shielding means, such as the loops 38, are provided. The support conductors 31 and 32, as shown, are preferably arranged with their ends in spaced apart alignment on the central axis of the anode sleeve, the filament 27 extending therebetween and being electrically and mechanically attached, at the opposite ends of the filament, to said spaced, aligned ends of the support conductors.

In order to insure against damage or destruction of the emission element 27 as a result of electrical discharge or flash-over from the anode to the emission element, flash arresting means is provided in the form of a flash receiving member or members, disposed preferably at the opposite ends of the emission element and electrically connected to drain off the flash energy, in harmless fashion, from the vicinity of the emission element. To this end, the flash receiving means may comprise a disk 39, as shown in Fig. 1, or a plurality of disks 39, as shown in Fig. 3, mounted on and electrically connected to one or other, or both, of the support conductors 31 and 32, in position at either or both ends of the emission element, and extending outwardly thereof toward the anode sleeve. As shown, the disks are electrically connected on, and supported by, the conductor 32, although it will be obvious that one of the disks could be mounted on, and electrically connected with, the conductor 31. The disks 39, 75 also, may be formed with central openings 40 for

receiving the filament connected ends of the conductors 31 and 32. If desired, the anode sleeve may be provided with an internal, annular rib or ribs 41, in position opposite the marginal edges of the disk or disks, in order to additionally channelize inverse discharges, to insure that the same take place between the anode sleeve and the edge portions of the disk or disks 39, to thereby afford positive assurance against the occurrence of any inverse discharge directly onto the emission filament. While the support conductors 31 and 32, the anode sleeve 19, and the arrestor disks may be made of any suitable or convenient material, it is preferable that these elements be made of metal having low electron emissivity; and, consequently, it is preferable that the anode sleeve, the support conductors, the disks, and also the ribs 41, where used, be made of molybdenum, which is a metal having low electron emission characteristics, although tungsten, and other suitable metals, may, of course, be employed.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

1. An electron flow device, comprising a sleeve-like anode and a cooperating cathode, including an electron emission element, mounted within and co-axially of said anode, support stems on which said element is mounted and between which it extends, flash arrestor means comprising a member on one of said support stems and extending outwardly of said element toward the anode to receive inverse anode discharge on said member, and means forming a discharge bead on said anode in registering alinement with said flash arrestor means.

2. An electron flow device, comprising a sleeve-like anode and a cooperating cathode, including an electron emission element, mounted within and co-axially of said anode, mounting means comprising support stems carrying said emission element in position therebetween and electrically connected therewith at the opposite ends of the element, and inverse flash arrestor means comprising members carried by said mounting means in position at the opposite ends of said emission element, said members having portions extending outwardly of said emission element toward said anode, to receive inverse anode discharge thereon for the protection of the emission element.

3. An electron flow device, comprising a sleeve-like anode and a cooperating cathode, including an electron emission element, mounted within and coaxially of said anode, and an inverse flash arrestor member of molybdenum mounted adjacent said emission element and having portions extending outwardly thereof toward said anode, to receive inverse anode discharge thereon for the protection of the emission element.

4. An electron flow device, comprising a sleeve-like anode and a cooperating cathode, including an electron emission element, mounted within and co-axially of said anode, an inverse flash arrestor member of molybdenum mounted adjacent said emission element and having portions extending outwardly thereof toward said anode, to receive inverse anode discharge thereon for the

protection of the emission element, and a discharge rib of molybdenum on said anode in registering alinement with said flash arrestor member.

5. An electron flow device comprising a sleeve-like anode and a cooperating cathode, having an elongated electron emission element mounted within and co-axially of said anode, including support stems having alined mounting ends on which the opposite ends of said emission element are electrically connected and between which said element extends, and an inverse flash arrestor means comprising a plate-like member supported on one of said stems adjacent an end of said emission element, said plate-like member having portions projecting radially outwardly of said emission element and said stems toward said sleeve-like anode for receiving inverse anode discharge on said plate-like member.

6. An electron flow device, comprising a sleeve-like anode and a cooperating cathode, having an elongated electron emission element, mounted within and co-axially of said anode, including support stems having alined mounting ends on which the opposite ends of said emission element are electrically connected and between which said element extends, one of said stems forming spaced loops encircling said element between the stem mounted ends thereof, and extending thence in spaced apart, side-by-side relationship with respect to the other stem, whereby both stems may be mounted on a common support spaced from an end of said emission element, and an inverse flash arrestor means comprising a plate-like member supported on said stem forming the said looped portions, said plate-like member having portions projecting radially outwardly of said emission element and said stem on which mounted toward said sleeve-like anode for receiving inverse anode discharge on said plate-like member.

7. An electron flow device, comprising a sleeve-like anode and a cooperating cathode, having an elongated electron emission element, mounted within and co-axially of said anode, including support stems having alined mounting ends on which the opposite ends of said emission element are electrically connected and between which said element extends, one of said stems forming spaced loops encircling said element between the stem mounted ends thereof, and inverse flash arrestor means comprising platelike members mounted on and electrically connected with said support means, at the opposite ends of said emission element, said arrestor means having portions projecting outwardly of said emission element toward said sleeve-like anode for receiving inverse anode discharge thereon.

8. An electron flow device, comprising a sleeve-like anode and a cooperating cathode, having an elongated electron emission element, mounted within and co-axially of said anode, including support stems having alined mounting ends on which the opposite ends of said emission element are electrically connected and between which said element extends, one of said stems forming spaced loops encircling said element between the stem mounted ends thereof, and inverse flash arrestor means comprising platelike members mounted on and electrically connected with said support means, at the opposite ends of said emission element, said arrestor means having portions projecting outwardly of said emission element toward said sleeve-like anode for receiving inverse anode discharge thereon, and riblike projections on and extending inwardly of said sleeve-like

7
anode in position registering with said platelike members.

9. An electron flow device, comprising a sleeve-like anode and a cooperating cathode, including an electron emission element, mounted within and coaxially of said anode, support stems on which said element is mounted and electrically connected, at its opposite ends, and between which it extends, one of said stems having portions extending radially outwardly of and alongside said emission element, and flash arrestor means comprising a disk mounted on a said support stem and electrically connected therewith at a mounting point radially outwardly of said emission element, said disk being supported in coaxial alignment with said emission element and extending radially outwardly thereof toward the

8
anode to receive inverse anode discharge on said disk.
